UNITED STATES PATENT OFFICE.

CHARLES R. SEYMOUR, OF ROCHESTER, NEW YORK, ASSIGNOR TO M. D. KNOWLTON COMPANY, OF ROCHESTER, NEW YORK, A CORPORATION OF NEW YORK.

BOX-COVERING MACHINE.

1,333,940.

Specification of Letters Patent. Patented Mar. 16, 1920.

Application filed August 4, 1917. Serial No. 184,460.

To all whom it may concern:

Be it known that I, CHARLES R. SEYMOUR, a citizen of the United States, and resident of Rochester, in the county of Monroe and State of New York, have invented certain new and useful Improvements in Box-Covering Machines, of which the following is a specification.

This invention relates to that class of machines which are adapted to apply a covering of paper to the tops and bottoms of paper or straw-board boxes or the like, and has particular reference to the mechanism for controlling the movement of the shearing knife.

An object of the invention resides in the provision of mechanically-actuated means for controlling the movement of the shearing knife which operates to sever the paper from the supply strip.

A further object of the invention resides in the provision of a mechanism which will automatically raise the knife to its initial or inoperative position and which will be reset for a subsequent operation.

A still further object of the invention resides in so constructing the mechanism that it will be controlled upon a movement of the work table.

In the drawings:—

Figure 1 is a side elevation of a portion of a topping machine with the invention applied thereto;

Fig. 2 is a front elevation of the same; Fig. 3 is an enlarged fragmental plan view showing the clutch shifting mechanism; and

Fig. 4 is a fragmental side elevation of the clutch shifting mechanism, also disclosing the actuating cam for the same.

In the drawings, a portion of a topper frame 1 is illustrated, at the upper portion of which is located a stationary knife or abutment 2, over which the strip of covering paper is adapted to be drawn in its passage from the supply roll to the work table. For coöperation with this stationary knife is a movable knife 3, carried by a rock shaft 4, and the movement of which toward the stationary knife is cushioned by a spring 5.

In order that the operator may bring about the movement of the knife 3 to sever the strip of paper at the desired times and without removing his hands from the work, the following mechanism is provided: A connecting rod 6 is attached at its upper

end to an arm 7 of the knife-carrying shaft 4, and at its lower end is pivoted at 6' to a lever 8, which latter is pivoted at 9 to a stationary casing 10 which provides a support for certain of the operating mechanism. The rod 6 is provided with a turn-buckle 11, so that its effective length may be varied at will. Thus, when the lever 8 is supported in its uppermost position, the knife 3 will be held in its raised or inoperative position, and when the support for the lever 8 is withdrawn, the knife 3 will be permitted to fall and coact with the stationary knife to sever the covering strip. Any suitable means may be provided for controlling the raising and lowering of the movable knife through this lever 8, the means here shown comprising a cam 12 mounted rigidly on a rotary shaft 13 and having an eccentric cam face 14 and an abrupt radial face 15. For coöperation with this cam 12, the lever 8 is provided with a projection 16, which normally rides on the peripheral or eccentric cam face 14, as shown in Fig. 4, whereby to hold the knife 3 in its raised or inoperative position.

The cam shaft 13, which is journaled in the casing 10, is driven from a shaft 17 through a suitable driving connection, such as for instance, as a worm and worm wheel 13' coöperating with a worm 17' on the shaft 17, which is also journaled in the casing 10, and is driven from a driving shaft 18 through the medium of a suitable friction clutch. This clutch comprises a socket member 19 and a cone member 20, the former of which is provided with a belt pulley 21 through which power is transmitted. The cone member 20 of the clutch is provided with a grooved collar 22, which is engaged by pins 23 on a shipper lever 24. This shipper lever 24 is pivoted at 25 to a projection 26 on the casing 10, and at its upper end is provided with a bifurcated portion 27. The cone member 20 is normally urged toward the socket member 19 by a coiled spring 28 which encircles the shaft 17 and expands between the collar 22 and an adjacent portion of the casing 10. A latch 29, which is pivoted at 30 to an arm 31 and is provided with an adjusting turn-buckle 32, projects through the bifurcated portion of the shipper lever 24 and is provided with a bill or hook 33 arranged to engage a plate 34 carried by said shipper lever. When this hook is in engagement with the plate 34, the cone

member 20 of the clutch is held out of engagement with the socket member 19, and consequently the latter runs idle and the shaft 17 is not actuated. The arm 31 to which the latch 29 is pivoted, is integral with a sleeve 35 which oscillates about a shaft 9 and with which the lever 8, previously referred to, is integrally formed. Thus, the latch 29 and the lever 8 will move 10 in unison as and for the purpose to be hereinafter described.

The work support, which includes the usual standard 37 and base 38, is supported by the frame 1, at 39 and is adjustable vertically, and also horizontally in both transverse and lateral directions, in the usual manner; the same being held in its adjusted position by means of suitable locking devices 40 and 41. Hinged at 42 to the base 38 is a 20 work table 43, which is normally urged upwardly by springs 44. Pivoted at 45 to a bracket 46 on the under side of the table 43, is a depending arm 47, which extends downwardly through an opening in the base 38 25 and is provided with a stop device 50 for engaging with a plate 48 on the under face of the base 38 to limit the upward movement of the table 43. The arm 47, at a point below the stop 50, is connected with 30 a lever which, as here shown, comprises a rock-shaft 53 journaled in a bracket 54 on the frame 1 and having two arms 52 and 52'. The arm 52, with which the table arm 49 connects, is keyed to the shaft 53 at 55, 35 so that it will rotate therewith, but be free to move longitudinally of the shaft, so that upon the lateral adjustment of the work support and table, said arm may be moved or adjusted in like direction. A pivotal connection of this arm 52 with the table arm 47 is here made by means of a clamping device 56 which adjustably engages the arm 47 through an elongated slot 49 therein. The second lever arm, 52', on the shaft 53, 45 is pivotally connected with a rod 58, which latter at its lower end is pivotally attached to the latch 29.

Assuming that the parts are in the positions illustrated in the drawings, the knife 50 3 will be in its raised or inoperative position and the loose pulley 21 will be running idly. When the operator desires to cause the knife to descend to sever the paper, it is only necessary for him to either press upon 55 the box which is supported by the table 43 and which is being operated upon, or to press upon the table itself. This downward movement of the table and connected rod 49 causes a rocking movement of the shaft 53 with its arms 52-52' and a consequent upward movement of the rod 58. Such movement of the rod 58 will raise the latch 29 about its pivot 30 and free the hook 33 from the plate 34. The spring 28 will then 60 operate to throw the cone member 20 of the

clutch into engagement with the socket member 19. This engagement will cause the rotation of the shaft 17 and, through the connection between this shaft 17 and the cam shaft 13, will cause the rotation of the 70 cam 12 in a counter-clockwise direction. Immediately upon this cam moving, the projection 16 on the lever 8 will ride off of the cam face 14 and drop over the face 15, and being connected to the movable knife 3 by 75 the rod 6, will permit the knife to drop under the action of gravity to sever the paper. The continued movement of the cam 12 will gradually raise the lever 8 and connected knife 3, until the projection 16 on 80 the lever reaches its initial position, that is to say, a position such as illustrated in Fig. 4, where it is about to pass off of the cam face 14.

When the lever 8 moves downwardly upon 85 being released by the cam 12, the latch 29 will be thrust forwardly and the hook 33 thereon will engage the plate 34 in the new position of the shipper lever 24, and, therefore, when the cam 12 again raises the lever 90 8 about its pivot, the latch 29 will be retracted, and because of its engagement with the shipper lever, will move the same against the action of the spring 28 and effect the disengagement of the clutch members 19 and 95 20. This disengagement of the clutch members occurs at such time that the cam 12 will stop its movement when the projection 16 on the lever 8 is located at substantially the highest point of the face 14, as illustrated in Fig. 4. Of course, it will be understood that after the depression of the table 43, it should be released to permit the table to again rise, at which time the hook portion of the latch 29 will drop on to the plate 100 34, so that upon the thrusting of the latch forward, the hook will engage said plate.

It will therefore be seen that for the operator to cause the severing of the paper and the resetting of the knife, it is only necessary 110 for him to depress the table 43. The remainder of the operation will be automatic and the knife will be reset for a subsequent operation which takes place only when the table is again depressed.

What I claim is:—

1. In a covering machine of the class described, the combination with a stationary knife and a coöperating gravity actuated knife, of means for holding the latter in its raised position, mechanically actuated means for rendering said holding means inoperative, and a movable work table for controlling the last-mentioned means.

2. In a covering machine of the class described, the combination with a stationary knife and a coöperating movable knife, of means for supporting the latter in a raised position, means for rendering said supporting means inoperative to support the knife,

- and means including a movable work-supporting table for controlling said last-mentioned means.
3. In a covering machine of the class described, the combination with a stationary knife and a coöperating movable knife, of means for supporting the latter, mechanically actuated means for rendering the supporting means inoperative to support the knife and for subsequently causing said means to raise the knife, and means, including a movable work table, for controlling the movement of the last-mentioned means.
4. In a covering machine of the class described, the combination with a stationary knife and a coöperating movable knife, of means for supporting the latter in a raised position, power-driven means for rendering the supporting means inoperative to support the knife and for subsequently raising the knife, and means, including a movable table, for controlling the power-driven means.
5. In a covering machine of the class described, the combination with a stationary knife and a coöperating movable knife, of a rod depending from the latter, a lever to which said rod is connected, a cam for supporting and raising said lever, a shaft for actuating the cam, and means, including a movable work table, for controlling the movement of the shaft.
6. In a covering machine of the class described, the combination with a stationary knife and a coöperating movable knife, of a rod depending from the latter, a lever to which said rod is connected, a cam for supporting and raising said lever, a shaft for actuating the cam, and means including a movable work-supporting table for controlling the movement of the shaft, said shaft being automatically rendered inoperative upon a complete operation of the knife.
7. In a covering machine of the class described, the combination with a stationary knife and a coöperating reciprocating knife, of power-actuated means for causing the reciprocation of the latter, and means, including a movable work table, for controlling said last-mentioned means.
8. In a covering machine of the class described, the combination with a stationary knife and a coöperating reciprocating knife, of means for supporting the knife, and means for rendering the latter inoperative to support the knife, said supporting means being subsequently active to render the last-mentioned means inoperative.
9. In a covering machine of the class described, the combination with a stationary knife and a coöperating reciprocating knife, of means for supporting the latter, automatic means for rendering the supporting means inoperative, and manual means, including a movable work table, for controlling the operation of the automatic means.
10. In a covering machine of the class described, the combination with a stationary knife and a coöperating gravity-actuated knife, of a movable work table, means for supporting the knife, means for releasing the knife to permit it to fall and to subsequently raise it to its inoperative position, and a connection between the table and last-mentioned means for controlling the same.
11. In a covering machine of the class described, the combination with a stationary knife and a coöperating movable knife, and a work table, of means for causing reciprocation of said knife, and connections between the work table and said means whereby the latter may be controlled from the former.
12. In a covering machine of the class described, the combination with a stationary knife and a coöperating movable knife, of power-driven means for causing reciprocation of the knife, said means including a shaft and a clutch member, manual means for rendering the clutch member operative, and automatically actuated means for rendering the clutch member inoperative.
13. In a covering machine of the class described, the combination with a stationary knife and a coöperating movable knife, of a cam arranged to support the latter in a raised position, but operative to permit the knife to fall, a shaft for actuating said cam, a clutch member on said shaft, manual means for rendering the clutch member operative, and means associated with and actuated by the cam for rendering the clutch member inoperative after a single reciprocation of the knife.
14. In a covering machine of the class described, the combination with a stationary knife and a coöperating movable knife, of a rod depending from the latter, a lever to which said rod is connected, a cam for supporting the lever to maintain the knife in its raised position, but operative to permit the lever and knife to fall, means for rotating said cam including a shaft and a clutch therein, a shipper lever for actuating said clutch, a latch associated with the first mentioned lever to engage the shipper lever and retain the clutch member in its inoperative position, and means for rendering the latch inoperative, said latch being arranged to engage the shipper lever upon the falling of the knife and to automatically disengage the clutch members upon the raising of the knife.

Signed at Rochester, in the county of Monroe, and State of New York, this 23d day of July, A. D. 1917.
